CLAIM

The ornamental design for a security tag, as shown and described.

DESCRIPTION

FIG. 1 is a top perspective view of a security tag in a disengaged state showing my new design;

FIG. 2 is a bottom perspective view of the design shown in FIG. 1;

FIG. 3 is a left side view of the design shown in FIG. 1;

FIG. 4 is a right side view of the design shown in FIG. 1;

FIG. 5 is a front view of the design shown in FIG. 1;

FIG. 6 is a rear view of the design shown in FIG. 1;

FIG. 7 is a top plan view of the design shown in FIG. 1;

FIG. 8 is a bottom plan view of the design shown in FIG. 1;

FIG. 9 is a top perspective view of a security tag in an engaged state showing my new design;

FIG. 10 is a bottom perspective view of the design shown in FIG. 9;

FIG. 11 is a left side view of the design shown in FIG. 9;

FIG. 12 is a right side view of the design shown in FIG. 9;

FIG. 13 is a front view of the design shown in FIG. 9;

FIG. 14 is a rear view of the design shown in FIG. 9;

FIG. 15 is a top plan view of the design shown in FIG. 9; and,

FIG. 16 is a bottom plan view of the design shown in FIG. 9.

The figures include broken, solid and dash-dot-dash lines. The dash-dot-dash lines illustrate an unclaimed boundary of the claimed design. The broken lines shown in the figures are included for the purpose of illustrating portions of the security tag and form no part of the claimed design.
